ATTORNEY

UNITED STATES PATENT OFFICE

ROBERT F. MORENUS, OF PORTLAND, OREGON

COMPACT

Application filed November 21, 1931. Serial No. 576,455.

This invention relates generally to toilet articles, and particularly to a compact.

The main object of this invention is to provide a new form of compact which will at all times completely separate the powder from the rouge and which at the same time will be convenient to operate and provide the maximum amount of capacity for ingredients and accessories for a given external dimension.

The second object is to so construct the compact as to expedite its manufacture and reduce its cost to a minimum.

These, and other objects, will become more apparent from the specification following as illustrated in the accompanying drawing, in which:

Fig. 1 is a perspective view of the closed compact.

Fig. 2 is a perspective view of the compact with one side open, the powder puff removed and the powder compartment open.

Fig. 3 is a perspective view of the opposite side of the compact showing its cover open with the rouge puff removed.

Fig. 4 is a section through the compact taken along the line 4-4 in Fig. 1.

Fig. 5 is a perspective view of the puff.

Similar numbers of reference refer to similar parts throughout the several views.

Referring in detail to the drawing, the compact consists of a somewhat rectangular frame including the ends 10 and 11 and the sides 12, between which sides 12 is placed a dividing wall 13. The wall 13 extends to the edges 14 but does not extend to the edges 15 of the sides 12. The wall 13 is joined along the edge 14 by means of a floor 16 to the end 10 where it is turned inwardly to form a supporting ledge 17 having a cover 18 which is joined by the hinge 19 to the wall 13. A suitable latch 20 is provided for holding the cover 18 in place. A lifter tab 21 is secured to the cover 18 for raising same when desired.

On the side of the wall 13 opposite the cover 10 and parallel with the floor 16 is a rouge compartment floor 22 which extends to the end 11, to which end is attached a powder compartment cover 23 by means of the hinge 24. A spring latch 25 is provided for the

cover 23 and a notch 26 is formed in the side of the cover 23 near the latch 25 to facilitate the opening thereof.

The space between the wall 13 and the end 11 constitutes a rouge compartment and contains a tray 27 for the rouge 28. A rouge puff 29 is stored directly against the rouge 28. A rouge compartment cover 30 is joined to the end 10 by means of a hinge 31. The cover 30 is provided with a latch 25 and a notch 26 similar to those on the cover 23. It is desirable to provide a powder puff 32 which extends across the outer side of the floor 22 and the cover 18.

It will be observed that the powder 33, which is normally in loose form, occupies the compartment between the wall 13 and the end 10 and that this powder is confined within the space provided therefor within the cover 18.

Either a separate mirror may be provided or the faces 34 of the members 16, 18, 22, 23 or 30 may be polished to form a mirror, or any of these surfaces may be provided with a glass mirror attached thereto without departing from the spirit of this invention.

It will be noted that in the compacts now in general use the openings are on the same side making it extremely difficult to prevent the puff and the rouge from becoming mixed, which is of course very objectionable from the user's standpoint. By having the hinges and snaps on opposite ends confusion in the opening of same is avoided.

I am aware that numerous changes in the details of this device may be made; I therefore do not intend to limit myself to the precise form illustrated and described herein, but I do intend to cover all such forms and modifications thereof as fall fairly within the appended claims.

I claim:

1. A compact consisting of a container divided into two compartments accessible from opposite sides of opposite ends of said container, a hinged cover for one of said compartments within said container, and outside covers for the opposite sides of said compact.

2. A compact consisting of a rectangular frame having a recessed compartment at one end of one side thereof and a second compart-

ment at the opposite end of the opposite side thereof, one of said compartments having a hinged closure within said frame, cover members for opposite sides of said frame hinged to opposite ends thereof, and means for latching said cover members independently into a closed position.

3. A compact having a rouge compartment at one end of one side thereof and a powder compartment at the opposite end of the opposite side thereof, and a closure for each side of said compact hinged thereto at the end opposite its respective powder or rouge compartment.

15 4. A compact having a rouge compartment at one end of one side thereof and a powder compartment at the opposite end of the opposite side thereof, and an independent closure for each side of said compact hinged thereto at the end opposite its respective powder or rouge compartment, said powder compartment having an independent closure within said compact.

25 5. A compact consisting of a rectangular receptacle having a transverse partition dividing same into two compartments, said compartments opening on opposite sides thereof, and a cover member for each side of said receptacle extending along the full length 30 thereof and hinged thereto at opposite ends of said receptacle.

ROBERT F. MORENUS.
